(57) **CLAIM**

The ornamental design of a palm sander, as shown and described.

DESCRIPTION

FIG. 1 is a front elevation view of a palm sander according to the present invention;
 FIG. 2 is a right side elevation view of a palm sander according to the present invention;
 FIG. 3 is a left side elevation view of a palm sander according to the present invention;
 FIG. 4 is a top plan view of a palm sander according to the present invention;
 FIG. 5 is a bottom view of a palm sander according to the present invention; and,
 FIG. 6 is a rear elevation view of a palm sander according to the present invention.
 The structural features depicted by means of broken lines in the drawing figures have been shown for illustrative purposes only and form no part of the claimed design.
